UNITED STATES PATENT OFFICE.

HERMAN A. METZ, OF NEW YORK, N. Y.

BOTTLE-STOPPER AND APPLICATOR.

1,089,717.

Specification of Letters Patent. Patented Mar. 10, 1914.

Application filed August 5, 1911. Serial No. 642,559.

To all whom it may concern:

Be it known that I, HERMAN A. METZ, a citizen of the United States, residing in the city of New York, borough of Brooklyn, county of Kings, and State of New York, have invented certain new and useful Improvements in Bottle-Stoppers and Applicators, of which the following is a full, clear, and exact specification.

10 This invention relates to a combined bottle stopper and device for removing and applying the contents thereof.

In the drawing accompanying and forming a part of this specification one form of my invention is illustrated.

The device herein illustrated is shown in position in the neck N of a bottle shown in dotted lines. In this particular form the central portion of the device consists of a 20 top T enlarged into the flange F so arranged as to fit over the lip of the neck of the bottle and further extended into the shank S of considerable less diameter than the neck of the bottle, the said shank being further extended into an enlarged portion E which is here shown of a globular form, two opposite sides R of which are shown have 25 been flattened. Surrounding the shank S is shown a bushing of elastic material B, 30 preferably cork, and surrounding the globular extension E is an absorbent material A attached to the shank S directly about the globular extension E by means of a wire, twine or other similar material H.

35 The above described bottle stopper is ap-

plicable for the closing of a bottle and for the removal of a portion of the contents by means of the absorbent material A.

The absorbent material is made preferably of felt and for its easy application to the stopper is preferably made of a thick cushion C of absorbent material at the center from which diverge two thinner portions or leaves K of the same material capable of being readily placed adjacent the flat surfaces of the extension and is shown attached to the intersection of the shank and the extension by means of wire or cord. The leaves are shown extending along the shank and the ends covered and held in position 50 by the bushing.

Various changes may be made in the structure illustrated without departing from the spirit of my invention.

Having thus described my invention I claim:

A bottle stopper comprising a top portion, a flange, a shank carried thereby having at its lower end an enlarged member, an absorbent material surrounding said enlarged member of the shank, and an elastic bushing surrounding the shank and portions of the absorbent material.

In witness whereof I have hereunto set my hand in the presence of two subscribing 65 witnesses.

HERMAN A. METZ.
